US0D1027184S

(12) **United States Design Patent** (10) Patent No.: **US D1,027,184 S**
(45) Date of Patent: ** May 14, 2024

(54) **EAR CLIP**

- (71) Applicant: **Socrates Health Solutions, Inc.**, Dallas, TX (US)
- (72) Inventors: **Scott J. Smith**, Dallas, TX (US); **Douglas E. Sutherland**, Luxembourg (LU); **Valentin Korman**, Huntsville, AL (US); **Tyde Meadows**, Hartselle, AL (US)
- (73) Assignee: **Socrates Health Solutions, Inc.**, Dallas, TX (US)
- (**) Term: **15 Years**
- (21) Appl. No.: **29/868,498**
- (22) Filed: **Dec. 5, 2022**

Related U.S. Application Data

- (63) Continuation of application No. 29/756,853, filed on Oct. 30, 2020, now Pat. No. Des. 974,569, which is a continuation of application No. 29/693,970, filed on Jun. 6, 2019, now Pat. No. Des. 903,878, which is a continuation-in-part of application No. 29/635,205, filed on Jan. 29, 2018, now Pat. No. Des. 855,808.
